O. WINSTON,
BULB STENCILING DEVICE,
APPLICATION FILED DEC. 7, 1916.

1,258,292.

Patented Mar. 5, 1918.

UNITED STATES PATENT OFFICE.

OVERTON WINSTON, OF MINNEAPOLIS, MINNESOTA.

BULB-STENCILING DEVICE.

1,258,292.

Specification of Letters Patent.

Patented Mar. 5, 1918.

Application filed December 7, 1916. Serial No. 135,580.

To all whom it may concern:

Be it known that I, OVERTON WINSTON, a citizen of the United States, residing at Minneapolis, in the county of Hennepin 5 and State of Minnesota, have invented certain new and useful Improvements in Bulb-Stenciling Devices; and I do hereby declare the following to be a full, clear, and exact description of the invention, such as will 10 enable others skilled in the art to which it appertains to make and use the same.

This invention relates to stenciling devices for use in applying wax coating to the main body of an electric light bulb to 15 thereby prepare the same for the application of frosted surfaces, and is in the nature of a modification of or improvement on the bulb stenciling device disclosed and claimed in my earlier pending application S. N. 20 134,284, filed of date December 1st, 1916, and entitled, "Bulb stenciling devices."

Generally stated, the invention consists of the novel devices and combinations of devices hereinafter described and defined 25 in the claims.

The invention is illustrated in the accompanying drawings wherein like characters indicate like parts throughout the several views. Referring to the drawings,

30 Figure 1 is a view chiefly in side elevation, but with some parts sectioned, showing the improved stenciling device and electric light bulb held thereby.

Fig. 2 is a bottom plan view of the parts 35 shown in Fig. 1; and

Fig. 3 is a section on the line 3—3 of Fig. 1.

The stenciling device comprises a suitable handle 4 having a curved extension bar or 40 plate 5 to which one or more stencil blocks are applied. The device shown is intended for use in producing two distinct frosted zones of the globe of the light bulb, and hence, the said bar 5 is provided with two 45 so-called blocks 6 and 7, both of which are formed with concave surfaces that closely fit the globe 8 of the light bulb. The shank of the light bulb is indicated by the numeral 9 and this shank is provided with the 50 customary diametrically offset lock studs or lugs 10. The bulb is of the two-filament type, being provided with filaments, the hot spots of which are indicated at *a* and *b*, the point *a* being at the axis of the bulb 55 and the point *b* being offset from the axis of the bulb.

The clamping lever 11 having an extended arm 12, is pivoted to the shank of the bar 5 at 13^a. The bar 11 and its arm 12 constitute an intermediate pivoted lever, 60 and the former is provided with an internally threaded head 13 into which a sleeve-like bulb receiving socket 14 is tightly screwed. The outer portion of the bore of this socket 14 closely fits the shank 9 of the 65 bulb and is provided with longitudinal grooves 15, through which the lock lugs 10 of the said shank are adapted to be passed inward and thereafter turned into engagement with an internal ledge or annular stop shoulder 16 of the said socket. A 70 coiled spring 17 attached at its outer end to the head 13 engages the end of the shank of the light bulb and frictionally holds the lock lugs 10 thereof engaged with the ledge 75 16, thereby holding the light bulb against accidental rotation, but permitting the bulb to be rotated on its axis so as to properly position its filaments *a* and *b*, in respect 80 to the frosted surfaces that are to be formed on the globe.

A leaf spring 18 is attached at one end to the shank of the bar 5 and its free end presses the arm 12 outward, so as to hold the light bulb in close engagement with 85 the concave face of the stencil locks 6 and 7.

When the bulb is held, as shown in Fig. 1, and is then dipped in paraffin, or other wax, all that surface of the bulb globe, except those portions covered by the stencil blocks 6 and 7, will be covered with wax, and then, when the globe is thereafter removed from the stenciling device, and dipped in acid or other liquid which, by its 90 chemical action on glass, will produce a 95 frosted zone, or which will otherwise produce a light dimming surface, the bulb will, of course, be provided with the frosted light dimming surface corresponding to the forms of the so-called stencil blocks. 100

After the bulb has been frosted, the wax may be readily removed by dipping the bulb in hot water.

In Fig. 1, the broken line *y* is a line drawn tangent to the bulb globe and 105 through the axis of the pivot 13. The broken line *y'* is parallel to the line *y* and intersects the extreme lower portion of the stencil blocks 6 and 7, and the broken line *y''* is perpendicular to the lines *y* and *y'*, 110 intersecting the axial filament *a* of the bulb, and bi-secting the line *y'*.

With this arrangement, therefore, the bulb will be pressed with equal force against both of the stencil blocks 6 and 7. The bulb in this device is also arranged to be held by its shank only, and by a socket that leaves the entire surface of the bulb globe exposed.

The curved bar 5 is shown as provided with two peek holes 19 and 20, through either of which the filaments of the light bulb may be viewed to determine when the bulb is properly set.

What I claim is:

1. A stenciling device for electric light bulbs comprising a handle having a curved extension bar provided with a plurality of stencil blocks spaced longitudinally thereof, a spring-pressed lever pivoted to said handle, a socket applied to one end of said lever and adapted to receive and to be interlocked with the shank of an electric light bulb, and a shank engaging spring within said socket.
2. A stenciling device comprising a handle having an extension bar provided with a stencil block, of a spring-pressed lever

intermediately pivoted to said handle, a sleeve-like socket applied to one end of said lever and provided with a shank engaging spring, said socket having longitudinal internal lock lug passages, and an annular internal stop ledge at the inner extremities of said lug passages.

3. A stenciling device comprising a handle having an extension bar, a stencil block applied to the extension bar, a lever pivoted to said handle and having an internally threaded head at one end and a socket sleeve screwed into said head, said socket sleeve having an internal lock shoulder and longitudinal lug passages leading thereto, and a coiled spring anchored to the said internally threaded head and engageable with the shank of an electric light bulb when held by said socket.

In testimony whereof I affix my signature in presence of two witnesses.

OVERTON WINSTON.
